LIFTING TONGS

Charles S. Dixon, Oakland, Calif.

Application August 13, 1947, Serial No. 140,838

Term of patent 14 years

(Cl. D44—29)

To all whom it may concern:

Be it known that I, Charles S. Dixon, a citizen of the United States and a resident of Oakland, in the county of Alameda and State of California, have invented a new, original, and ornamental Design for a Lifting Tongs, of which the following is a specification, reference being had to the accompanying drawings, forming part thereof, wherein

Figure 1 is a perspective view of a lifting tongs embodying my new design, the tongs being in work-receiving condition.

Figure 2 is a side elevation of the tongs, the tongs being in closed condition.

Figure 3 is a plan view of the tongs in collapsed condition.

I claim:

The ornamental design for a lifting tongs, substantially as shown.

CHARLES S. DIXON.
